UNITED STATES PATENT OFFICE.

JOSEPH C. FELDMAN, OF NEW YORK, N. Y., ASSIGNOR TO TILLIE K. FELDMAN, OF NEW YORK, N. Y.

ELECTRIC WATER HEATER.

Application filed December 6, 1923. Serial No. 678,800.

To all whom it may concern:

Be it known that I, JOSEPH C. FELDMAN, a citizen of the United States, residing at New York city, borough of Manhattan, in the county of New York and State of New York, have invented certain new and useful Improvements in Electric Water Heaters, of which the following is a specification.

This invention relates to automatic electric water heaters of the general character described and claimed in Letters Patent of the United States No. 1,299,159, issued on the 1st day of April, 1919, to Tillie K. Feldman.

Among the objects of the present invention is to simplify and therefore generally improve the construction, operation, and reliability of the controlling mechanisms for both the current of electricity and water delivery.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view on the line 1—1 of Fig. 2.

Fig. 2 is a plan view of the principal parts of Fig. 1.

Fig. 3 is a horizontal section on the line 3—3 of Fig. 1.

Fig. 4 is a vertical section on the line 4—4 of Figs. 1 and 3.

Fig. 5 is a rear elevation of the switch mechanism as would be seen from the line 5—5 of Fig. 1.

Fig. 6 is a view of the same mechanism with the switch closed.

Fig. 7 is a detail view of the valve actuator or knuckle.

Referring now more specifically to the drawings, my invention will be understood as comprising a base 10 having an open bottom and to which are connected suitable supporting feet or legs 11 and within which is located the water valve mechanism and means for passing water through the device. This base includes a top or cap 12 having downwardly projecting bosses 13 and 14 for

the attachment of the water supply pipe 15 and delivery pipe 16, as by means of locking nuts 17. This cap plate is provided with a counter sink 18 in its upper surface.

Secured upon the seat or counter sink 18 is a heating unit comprising a cylindrical body of porcelain 19, a surrounding shell 20, a binding cap 21, and a dome 22. The cap 21 has a seat 21' in its under surface, and suitable packing members or gaskets 23 are fitted against the top and bottom ends of the body 19 for making a water tight seal for this member, and the cap 21 is bound in place by means of vertical tie rods 24 fixed as by screw threads in holes 25 in the base plate 12 and having binding nuts 26 bearing against the top of the cap 21. These nuts 26 serve incidentally as ornamental features of the construction. The dome 22 is shown as hemi-spherical. Its primary function is to inclose certain electrical connections and it too serves an ornamental office. This member is shown as secured in place by means of a central stud 27 with which cooperates a top cap nut 28. Said stud 27 is fixed in the center of the body cap 21.

The porcelain or the like body 19 is provided with any suitable channels 29 for the passage of water into and through said body, and threaded through said channels is a resistance coil 30, the terminals of which are connected to binding screws 31 passing through the body cap 21 and having secured to their upper ends within the dome 22 the leads 32 from any suitable source of electricity.

33 indicates a valve casing located within the hollow base 10 and having its front end secured against the front wall of said base as by means of a faucet body 34 having a threaded boss 35 projected rearward through said front wall of the base and tapped into said front end of the valve casing. A packing gland 36 seals the front end of said faucet body, and a gland 37 seals the rear end of the valve casing.

An actuator or rock shaft 38 is journaled horizontally through the base 10 and valve casing 33, having bearings in the aforesaid glands and also in a center bearing 39 of the valve casing and also at the rear wall of the base at 40. A suitable handle or knob 41 is secured to the front end of the rock shaft for manipulating it into vertical neutral position or to the right or left accord-

ing to whether hot or cold water delivery is desired. As indicated in Figs. 1 and 2 the valve mechanism is adjusted for cold water delivery. A collar 42 is fixed upon the rock shaft within the rear wall of the base to limit the rearward movement thereof. The water delivery pipe 16 communicates with a downward extension 43 of the valve casing, and a valve 44 adapted to close upward by the combined force of the water flow and a spring 45 controls the delivery of water from said extension and pipe 16 toward the faucet. Said valve and spring are held in place by a plug 46 threaded into the lower end of said valve body extension 43. The valve 44 is provided with an upwardly projecting stem 47 which extends through an opening through the valve seat 48 toward the rock shaft 38, but has co-operation with a cam 49 fixed to said shaft. This cam is largely circular and concentric with the shaft but has a reduced or flattened side 49', which when registering with the valve stem 47 will permit the valve to close upon its seat 48 and thus prevent the delivery of water through the faucet. Any suitable means, as for example the collar 42 co-operating with the rear leg attachment lug may be provided to limit the rotation of the rock shaft within 180°, one extreme position being that for cold water as in Figs. 1 and 2 at which time the flat side 49' of the cam is located about 90° from the stem 47. With the rotation of the rock shaft and handle 41 in a clockwise direction as from the front, the flat side of the cam comes into registry with the stem and it permits the valve to close. At this time the handle will be vertical and no water will be delivered. Obviously rotation of the rock shaft in either direction from its neutral position of the cam will cause the opening of the valve and cold water will be delivered at such times except when the electric switch now to be described is closed.

At the rear of the apparatus I provide a vertically arranged switch casing 50 having a rear door or closure 51. The electric wires 32 above described are led into the upper portion of the casing through holes 53. One of these leads 32 within the upper portion of the casing is parted and suitably connected at spaced points 54 to two fixed contact studs 55. A shelf or plate 56 forming a partition for the top of the casing is secured in place with respect to the extreme top by means of a stud 57 having a head on the lower end and connected by means of a screw 58 at its upper end. The rear end of the rock shaft 38 is located within the casing 50, and fixed to said rock shaft adjacent to the outer surface of the rear wall of the base 10 is an actuator or knuckle 59 comprising a hub 60, a radially projecting finger 61, and a lug 62 parallel to the axis

of the knuckle and offset radially from the hub 60. The lug 62 projects longitudinally of the actuator beyond the end of the hub. Being fixed to the rock shaft this knuckle rotates with it.

Journalized loosely upon the rearwardly projecting end of the rock shaft and close to the rear end of the hub 60 is a switch arm 63 carrying at its upper end a switch plate or bridge 64 adapted to engage both the studs 55 and complete the circuit there-through. This bridge piece or plate is carried by a block 65 of fiber or the like through which a pair of pins 66 project laterally through corresponding holes in the upper end of the arm. These pins are adapted to slide through said holes, and springs 67 surrounding the pins normally urge the plate or bridge 64 toward the studs 55.

Co-operating with or between the rock shaft 38 and the arm 63 is a strong spring 68 tending to throw the arm away from the studs 55 and against the remote side of the casing 50 as in Fig. 5, one end of the spring bearing against the arm and the other end bearing against the bottom of the casing, the intermediate portion of the spring being coiled around the extreme rear end of the rock shaft and held thereon as by means of a cotter 69 and so serving incidentally to hold the arm 63 in place.

Between the shaft 38 and the free end of the arm it is provided with a pair of transverse holes 70 and 71 through which are slidably fitted a locking pin 72 and a releasing pin 73 respectively. These pins are connected to a leaf spring 74 secured at its upper end as by a screw 75 to the arm. As shown clearly in Fig. 1 these pins are adapted to project through and beyond said holes in the arm, and the locking pin, by virtue of the spring 74, is adapted to snap inward into engagement with the end of a stop 76 fixed to the inner wall of the casing and located sufficiently far from the actuator or knuckle to permit the finger 61 to pass beneath it while making rotation with the valve mechanism. Hence said finger 61 by a wiping action serves to press the pin 73 outward and so withdraw or release the locking pin 72 from its holding position.

It being understood that the position of the knuckle in Fig. 5 approximates the position to be occupied by it when the handle 41 is turned for the delivery of cold water, a rotation of the handle and rock shaft toward its opposite position or toward the left as in Figs. 5 and 6, will bring the lug 62 into contact with the edge of the arm and so bring said arm and its circuit closing bridge 64 into the position shown in Fig. 6, closing the circuit. During the latter part of this movement of the arm the operator applies sufficient force to it to compress the springs 67, making a more reliable contact between

the studs 55 and permitting the locking pin 72 to snap over the end of the stop 76. This locking pin as described and shown in Fig. 6 serves to hold the switch arm in closed position and against the force of the spring 68. At this time the releasing pin 73 will have passed inward to the rear of the finger 61. At this time the circuit will be closed and the valve 44 will be opened by the action 10 of the cam 49 for the delivery of water which is being heated as it passes through the body 19 as a result of its contact with the resistance coil 30. It is obvious that a full stroke of the valve handle toward the 15 right is necessary to close and lock the switch closed to insure the delivery of hot water. Otherwise the spring 68 will throw the switch toward the position of Fig. 5. To cut off the hot water, however, the operator 20 has simply to actuate the handle slightly in a reverse direction to cause the finger 61 to release the locking pin and permit the switch arm to snap to its spaced position as in Fig. 5.

25 It will be appreciated that this mechanism is of a most simple, compact, and hence reliable nature, sure to operate and is proving in practice most satisfactory.

I claim:

- 30 1. The herein described switch mechanism for automatic water heaters comprising a pair of spaced contact studs, a bridge, a switch arm carrying at its free end said bridge, a manually operated rock shaft on 35 which the end of the arm remote from the bridge is journaled freely, a spring acting upon the arm tending to throw it in one direction to open the switch, an actuating knuckle fixed to the rock shaft and having 40 lost motion engagement with the arm for positive movement thereof in the opposite direction against the force of said spring, and locking means for the switch arm releasable by said knuckle to permit the switch 45 to open under actuation of the spring.
2. Mechanism as set forth in claim 1 in which the actuating knuckle co-operates with the arm to close the switch at the time the rock shaft is making the last part of 50 its movement in one direction, and locking means is provided co-operating with said

arm to hold it in circuit closing position after the switch is closed, said knuckle having means for releasing said locking means when the rock shaft is turned in the opposite direction. 55

3. The herein described switch mechanism for an automatic water heater comprising circuit closing means having a switch member, an actuator to co-operate with said switch member, resilient means tending to automatically move said switch member to break said circuit, and locking means for automatically locking said circuit closing means to retain the circuit closed, said actuator having means both to close said circuit closing means and to release said locking means when the circuit closing means is to be opened to permit the aforesaid automatic means to operate the circuit closing 70 means, said actuator having spaced means comprising a plurality of members one of which is adapted to actuate said circuit closing means to close the same against the force of said resilient means, while the other 75 is adapted to release said locking means when the circuit is to be opened.

4. The herein described switch mechanism comprising spaced contact means for actuating the same including a switch arm, a shaft upon which said arm is mounted for swinging movement to close the switch, resilient means co-operating with said switch arm tending to open the switch, means for locking the switch arm in closed position 80 including a member mounted on the switch arm and arranged for movement thereon, and a knuckle mounted on said shaft and movable relatively to said switch arm, said knuckle having a plurality of spaced extensions at a face thereof, one of which forms an abutment for the switch arm arranged to strike and close the switch when the knuckle is rotated in one direction while the other forms a cam arranged to move 85 in contiguity to said switch arm when the knuckle is rotated in the opposite direction to move said locking means as aforesaid and permit the switch to be opened. 90

95 In testimony whereof I affix my signature.

JOSEPH C. FELDMAN.
